(57) **CLAIM**

We claim the ornamental design for a television assembly with rollable display and drawers, as shown and described.

DESCRIPTION

FIG. 1 is a front, top perspective view of a television assembly with rollable display and drawers, showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a rear perspective view thereof;

FIG. 9 is a perspective view thereof showing a state that the lower drawer is opened;

FIG. 10 is a front, bottom perspective view thereof, with an enlarged detail view;

FIG. 11 is a front, top perspective view of the television assembly with rollable display and drawers of FIG. 1, shown with the upper drawer partially opened;

FIG. 12 is a front elevation view thereof;

FIG. 13 is a rear elevation view thereof;

FIG. 14 is a left-side elevation view thereof;

FIG. 15 is a right-side elevation view thereof;

FIG. 16 is a top plan view thereof;

FIG. 17 is a bottom plan view thereof;

FIG. 18 is a front, bottom perspective view thereof, with an enlarged detail view;

FIG. 19 is a front, top perspective view of the television assembly with rollable display and drawers of FIG. 1, shown with the upper display partially rolled down;

(Continued)

FIG. 20 is a front elevation view thereof;
 FIG. 21 is a rear elevation view thereof;
 FIG. 22 is a left-side elevation view thereof;
 FIG. 23 is a right-side elevation view thereof;
 FIG. 24 is a top plan view thereof;
 FIG. 25 is a bottom plan view thereof;
 FIG. 26 is a front, top perspective view of the television assembly with rollable display and drawers of FIG. 1, shown with the upper display fully rolled down;
 FIG. 27 is a front elevation view thereof;
 FIG. 28 is a rear elevation view thereof;
 FIG. 29 is a left-side elevation view thereof;
 FIG. 30 is a right-side elevation view thereof;
 FIG. 31 is a top plan view thereof; and,
 FIG. 32 is a bottom plan view thereof.
 Broken lines and unshaded surfaces adjacent to broken lines illustrate portions of the television assembly with rollable display and drawers that form no part of the claimed design.
